GAS-LIFT PUMPING SYSTEM

Lilburn J. Tomlinson, Long Beach, Calif.

Application February 10, 1953, Serial No. 336,098

3 Claims. (Cl. 103—52)

This invention relates to the production of liquids from wells. More particularly, the invention relates to an improved plunger gas-lift system for pumping oil and/or water from a well by means of a compressed gas.

Essentially, plunger lift equipment comprises a string of production tubing in which a freely moving plunger travels the entire distance from the wellhead to the bottom of the tubing and back to the wellhead on each stroke.

On each trip to the surface, the plunger lifts a column of liquid, such as oil. The plunger is in turn propelled on its upward trip by the pressure of gas under it in the tubing, which gas is supplied by a parallel string of injection tubing. The production tubing is connected at the surface to a flow head to receive the liquid lifted by the plunger and direct it through flow lines to storage or transport. As soon as the plunger has delivered its load at the wellhead and the lift gas pressure is released thereby, liquid begins to flow from the well into the lower end of the tubing. Release of gas pressure occurs when a valve in the plunger is opened upon striking a wellhead bumper. The plunger falls freely through any fluids back into the well string by gravity alone and the valve in the plunger is closed as the plunger falls at the end of the down stroke upon a bumper in the footpiece fitted at the lower end of the tubing.

Regulatory bodies in some oil producing states have placed restrictions upon the output from oil wells. This makes it necessary to reduce the number of cycles which the plunger makes during any given period if the well is to be kept in continuous production on a limited quota basis, or to shut down the well when the allotted quantity of oil has been produced. A consequence of a shutdown is an expense in returning the shut-in well to production again, as by swabbing or bailing. Restrictions are also placed upon the quantity of gas which may be produced from a gas-oil well with respect to the amount of oil produced in order to conserve the gas and maintain the formation pressure for as long as possible. Where a quota has been set on gas, it may be the controlling limit before the oil quota is reached. In such cases it is desirable to reduce the gas to oil ratio to increase oil production to its maximum.

The improved gas-lift pumping system of this invention is particularly applicable to producing oil in areas which also produce natural gas. This gas under pressure provides the power for raising the oil. Such gas may flow within the casing from the oil zone being produced, from a separately produced zone in the same well, or from a neighboring well. If the gas is not obtainable at sufficient natural pressure, it is passed through a booster pressuring pump before use. Although the greatest utility of the improved pump is in gas-oil producing areas, it may be used elsewhere in the absence of natural gas by compressing air, CO_2 , and the like to the requisite lifting pressure.

It is accordingly one object of this invention to provide an improved time controlled plunger lift system to permit controlled rates of production over a desired period of time heretofore not possible of achievement, thus avoid-

2

ing expensive swabbing to return shut-in wells to production.

A further object is to provide an improved gas-lift system by the use of which gas-oil ratios can be kept to a minimum to conserve natural gas.

Another object is to utilize formation gas efficiently to raise a maximum quantity of oil per pressured quantity thereof.

A still further object of this invention is to provide an improved system whereby back pressure of gas in the production string may be reduced to a minimum to facilitate the inflow of oil to the bottom section thereof between lifting strokes of the plunger.

Other objects of the invention will appear as the description proceeds.

To the accomplishment of the foregoing and related ends, this invention then comprises the features hereinafter fully described and particularly pointed out in the claims, the following description setting forth in detail certain illustrative embodiments of the invention, these being indicative, however, of but a few of the various ways in which the principle of the invention may be employed.

In the drawings: Figures 1-8 are concerned with an embodiment of my invention employing pneumatic controls. Figure 9 illustrates another embodiment of my pumping system employing electrical controls. Each figure of the drawings is further identified as follows:

Figure 1 is an elevation view, partly broken away, showing one form of the improved gas-lift system of this invention.

Figure 2 is a detail view partly in section on an enlarged scale showing the plunger catcher assembly at the wellhead. This same assembly is also shown and, in part, in section, in Figure 2a.

Figure 3 is a detail view, partly in section, of a plunger-actuated trip mechanism for controlling shut-off of the lift gas supply.

Figure 4 is a detail view, partly in section, on an enlarged scale of a pressure-spring actuated piston assembly by which the time control mechanism is actuated.

Figure 5 is a diagrammatic plan view of one form of the time control device which may be used in the system of this invention.

Figure 6 is a diagrammatic elevation shown the piston of the pressure-spring actuated piston assembly and the arm controlling a pressure bleed-off sleeve valve in up position.

Figure 7 is a similar diagrammatic elevation showing the piston and arm in down position.

Figure 8 is a diagrammatic showing of the operation of a time control mechanism used in the system of this invention.

Figure 9 illustrates the use of electric controls at the wellhead for controlling the pumping cycle and lift gas supply.

Briefly summarized, the sequence of the automatic and timed controlled stepwise operations provided in the present pumping system are as follows: (1) The lift gas supply is shut off at a desired point prior to complete delivery at the wellhead of the oil column lifted by the plunger. (2) At pre-set timing device is put into motion upon shutting off the lift gas. (3) The plunger on reaching the wellhead completes the delivery of a column of oil and the valve in the plunger is opened by the plunger striking a wellhead bumper whereupon the remaining lift gas pressure is diminished by flow of gas after the delivered oil. (4) The plunger falls back upon a catcher in the wellhead and remains there for a pre-set time interval. (5) After this time lapse, the timing device actuates release of the catcher and the open-

valved plunger falls freely into the production tubing. (6) After a further pre-set time lapse, preferably when

the plunger has fallen through an accumulated column of oil in the production tube of the well and the plunger valve has closed upon striking a bottom tube bumper, the lift gas supply is turned on by the timing device. Thus the pumping cycle is continuously repeated. Setting the holding time at the plunger catcher determines the frequency of pumping and thus permits the relative continuous productivity of a well at allowable levels below its maximum capacity. Controlling the flow of lift gas prevents free-flowing wastage with fullest utilization of the pressured gas for lifting oil. Thus, operations are maintained at the least possible gas to oil ratio. Provisions for accomplishing this controlled operational sequence will be seen in the drawings and the description of the pumping system hereinafter.

Referring more specifically to the drawings and more especially to Figure 1, there is here illustrated a well provided with a casing generally indicated at 1 extending into a producing zone within the earth. Within the casing are two parallel strings of tubing, tube 2 being a lift gas injection string and tube 3 being a production string. The injection tube and the production tube are held together by clamp 4. A conventional valved plunger indicated generally at 5 is freely movable in the production tube, adapted to travel the entire distance from production zone to wellhead. A footpiece assembly represented generally at 6 connects the bottom ends of the two strings of tubing adjacent the production zone and is equipped with a spring loaded ball and seat check valve 7 to prevent flow of well liquids into the gas injection tube 2. A conventional bottom lock hold-down shoe 8 is positioned in the production tube above the footpiece 6 to hold in place a retrievable bumper spring assembly 9 which is employed to stop the downward fall of the plunger 5 and to shut the valve contained in said plunger assembly when the plunger falls thereon. Another bottom lock hold-down shoe 10 is positioned below the foot-piece 6 in the production string to hold in place a retrievable spring loaded ball and seat standing check valve 11 which prevents the back flow of the liquid or gas into the well bore and formation as the lift gas pressure is applied to lift the liquid load upon the plunger to the surface; thus a closed type of gas-lift plunger pump is provided. A tail pipe 12 can be employed below shoe 10, if desired, to permit the production of well liquid from a sump at the bottom of the well bore.

Well casing 1 terminates at its upper end at the earth's surface in an assembly comprising generally wellhead 13 into which production string 3 leads and from which flow pipe 14 extends to carry off the well product to a gas-oil separator and storage vessel or transport not shown. Within wellhead 13 is a top bumper spring and valve opener which stops plunger 5 at the end of its upward travel. At the wellhead in production string 3 is a spring loaded catcher assembly 15, more fully described hereinafter with reference to Figure 2, to hold plunger 5 at the wellhead after delivery of a column of oil. The catcher 21 within catcher assembly 15 is actuated to release the plunger by pressure changes transmitted through pressure line 16 to diaphragm housing 17 controlled by a pressure-operated time cycle intermitter indicated generally at 18 and described more fully hereinafter with reference to Figures 4, 5, 6, 7, and 8. The lift gas supplied under suitable pressure from a source previously described flows through line 19 to injection tube 2. Flow of gas to the injection tube is controlled through valve 20 actuated by time control device 18 in a manner hereinafter described in detail.

Referring now to Figures 2 and 2a, production string 3 is intercepted by the plunger catcher assembly 15. Catcher 21 is slidably mounted in sleeve 22 of the assembly joined by rod and sliding clevis arrangement 23 to diaphragm 24 in diaphragm housing 17. Coil spring 25 urging against diaphragm 24 causes catcher

21 to be retracted from production tube 3 as pressure is released from chamber 24a. Pressure line 16 leads to pressure chamber 24a in diaphragm housing 17. The trip mechanism, cam 26 et seq., in Figure 3 may be positioned on the production tube either at the well-head or elsewhere along the upper length of the string. The upward velocity of the plunger will accelerate as soon as the weight of the liquid column thereon starts decreasing by unloading through delivery line 14. The lift pressure, therefore, becomes decreasingly less than that required initially to move the liquid column up the production tube. To prevent undue acceleration and impact of the plunger against the wellhead, the location of the trip mechanism will be preferably far enough below the wellhead so as to shut off the lift gas supply early enough for expansion-reduction of pressure to meet the decreasing pressures required during liquid unloading. Thus, undue acceleration of the plunger can be avoided. The trip mechanism comprises cam 26 pivotally mounted at 27 and urged by coil spring 28 attached to arm 29 so as to extend a short distance into the path of plunger assembly 5 in production tube 3. Arm 29 is joined to the needle bleed-off valve 30 which in turn is connected through line 31 to pressure chamber 32 in the piston assembly 33 of Figure 4. Piston 34 within pressure chamber 32 is joined through rod 35 to piston head 36. Gas pressure is induced in chamber 32 through port 37 from the injection gas supply line. Piston 34 is urged upward within chamber 32 by means of coil spring 38. Piston assembly 33 is positioned within time cycle intermitter 18, as shown in Figures 5, 6, and 7. Cam follower 39 is pivotally spring mounted above piston 36 and joined to flapper disc 50 (as shown in Figure 8) in housing 40 to actuate the gas control valve 20 in line 19. Timer wheel 41 is rotatably mounted within housing 18 adjacent to the cam follower 39 and is driven by suitable spring, electric, or fluid power means. Timer wheel 41 carries a plurality of flapper disc closing lugs 42 upon its upper surface and a plurality of sleeve valve opening lugs 43 on its perimeter. Sleeve valve 44 is positioned adjacent timer wheel 41 to permit the spring mounted arm 45 to be contacted by lugs 43. Sleeve valve 44, upon lifting of arm 45, bleeds off pressure (supplied by control gas pressure line 46) from line 16 to chamber 24a in plunger catcher diaphragm housing 17 so as to withdraw catcher 21 and release the pump plunger.

In Figure 8, control gas pressure line 46 supplied from lift gas line 19 or some other source, such as compressed air, leads into housing 40. Within the housing 40, the restricted orifice 48 is smaller than orifice 49. Flapper disc 50 attached to the cam follower 39 is held against orifice 49 by coil spring 51. Housing 40 leads to a diaphragm housing containing pressure chamber 53 and diaphragm 54. Gas control valve 20 is actuated by diaphragm 54 through connecting rod 56, the valve being urged shut in the absence of pressure in chamber 53 by coil spring 55. Time cycle intermitters of several types are per se old and available commercially. One type of time cycle intermitter which may be readily modified to be adapted to the operation of the improved gas-lift pumping system of this invention, as shown in Figures 5 to 8, is available as Type 4655B from the Fisher Governor Company of Marshalltown, Iowa.

In the operation of the system of this invention, as in an oil well, oil flows from the subsurface formation by gravity and formation gas pressure through tail pipe 12 and check valve 11 into the lower end of production tube 3 to form a column of oil therein. The valve of plunger 5 being open, the plunger will drop freely through such liquid to bumper 9 which closes the plunger valve. Gas under pressure is introduced into the production tube under the plunger from line 19 through injection tube 2 and check valve 7 in footpiece 6 forcing the plunger upward carrying before it the column of oil

accumulated in the production tube. At the wellhead the oil produced flows through line 14 to storage or transport. As the plunger passes the trip cam 26 in the production tube, the injection gas supply is shut off. This occurs as follows: the plunger depresses cam 26 unseating needle valve 30 causing a bleed off of pressure through line 31 from chamber 32 of piston assembly 33 mounted in the diaphragm case of the pressure operated time cycle intermitter 18. The release of pressure from pressure chamber 32 above pressure-spring actuated piston 34 allows coil spring 38 to push the piston upward, piston head 36 in turn raising cam follower 39 to a position riding the rim of the timer wheel of the time cycle intermitter, thereby holding flapper disc 50 away from orifice 49 thus allowing pressure to bleed from the upper diaphragm pressure chamber 53 faster than it can be replaced through the restricted orifice 48 and at the same time actuating switch 47 to begin the movement of timer wheel 41. As the pressure in chamber 53 decreased, the coil spring 55 urges diaphragm 54 and connecting rod 56 upward, closing valve 20 and shutting off the injection gas supply.

The plunger after striking the top bumper spring in the wellhead comes to rest on catcher 21 which extends out into the production tube. The plunger valve has opened upon the plunger striking the top bumper spring. After being actuated by the piston head 36 through switch 47, the timer wheel 41 driven by motor 47a begins to rotate slowly in a counter-clockwise direction. After a pre-set interval of time as determined by the positioning of sleeve valve opening lugs 43 on the perimeter of the clock wheel, spring mounted arm 45 on sleeve valve 44 is raised by a lug 43 bleeding off pressure from the diaphragm chamber 24a in diaphragm housing 17, allowing coil spring 25 to retract catcher 21 thus permitting the plunger to return to the producing zone to begin another cycle. After arm 45 passes over lug 43 and returns to its normal position, the bleed-off port is closed, pressure is supplied to chamber 24a, and catcher 21 returns to catching position in the production tube. When plunger 5 drops through the production tube on its way back to the producing zone, it again actuates piston head 36 by tripping cam 26, unseating needle valve 30 causing a bleed off of pressure through line 31 from pressure chamber 32 of piston assembly 33 allowing coil spring 38 to push the piston upward. However, because cam follower 39 is at this time riding on top of timer wheel 41, the piston merely moves up and then falls back down after the plunger has passed cam 26 resetting the release mechanism for the next cycle and nothing further happens until the next stage of activity is actuated by movement of the timer wheel. After a predetermined longer period of time as determined by the positioning of flapper disc closing lugs 42, the cam follower 39 riding the outer rim of timer wheel 41 is forced off this wheel, actuating switch 47 to halt rotation of the timer wheel and allowing flapper disc 50 to close orifice 49 thus permitting pressure to build up in chamber 53 against diaphragm 54 urging connecting rod 56 away to open valve 20 in injection gas line 19 permitting a build-up of gas under the plunger and thus begin a new cycle. Thereafter the cycles are repeated continuously. It will be noted that when the lift plunger 5 is released and dropped into the well, it will again depress the trip cam 26. However, the cam remains inoperative at this point until a time thereafter when a lug 42 on the timer wheel 41 has forced the follower 39 back onto piston head 36.

The length of the pumping cycle, regulated by the positioning of the lugs 42 and 43 on timer wheel 41, may be varied from a fraction of an hour to several hours dependent upon a number of circumstances such as the number of cycles in any given calendar period required to produce the allowable quantity of petroleum fluids, the depth of the well which determines the time of actual plunger travel, the rate of flow of the well 76

fluid into the foot of the production tube, and the like. The longer pre-set time interval regulating resumption of flow of the lift gas must be enough longer than the first pre-set time interval for dropping the plunger so as to allow the plunger to return to the bottom of the well and close its valve before gas flow is resumed for oil lift.

Referring now to Figure 9, there is shown an electrical arrangement in conjunction with the wellhead section for controlling the pump cycling in my improved plunger gas-lift pumping system. Certain of the parts shown in this figure which correspond to like parts in the preceding description are designated by like numbers. The operation of the pump with electrical timing controls is as follows: Plunger 5 propelled by gas supplied under pressure from line 19 through open valve 20 and injection tube 1, as already described, has delivered a column of oil into flow pipe 14. In so doing, plunger 5 has in passing, depressed cam 26, thus closing spring switch 57 momentarily whereby relay 58 de-energizes solenoid 59 through circuit 60 to close the lift gas supply valve 20 urged by spring 55. Valve stem 56 includes a movable armature shaft extending into solenoid 59. This operation of relay 58 also closes circuit 61 to start the timer motor 62, and readies relay 63 by closing switch 64 to become operative at a later pre-set time interval. Plunger 5 has completed delivering the oil into flow pipe 14, has struck the bumper spring 13 which opens the plunger valve, and the plunger has come to rest on its catcher 15 as shown in the drawing. Meanwhile, the timer motor 62 is operating, having been started by movement of cam 26 just described; the timer cams 63 and 64 are rotating so that each will come into electrically actuating positions at a pre-set time interval. Cam 64 comes into actuating position at a time subsequent to that for cam 63. The pumping cycle waits upon the now rotating timer cam 63 with plunger 5 being held on catcher 15 which is in the production tube 3 by means of spring 67. The plunger 5 is dropped into the well when cam 63 has rotated until the notch therein has dropped spring arm 65 which closes circuit 66 to energize solenoid 68 and withdrawn catcher 15 attached to a movable armature therein. Although cam 26 becomes depressed again as the plunger drops by, there is now no operative effect upon the control mechanism as will be seen from the circuiting thereof. As cam 63 continues to rotate, spring arm 65 is raised, opening circuit 66 to de-energize solenoid 68 and catcher 21 is returned by spring 67 to the catching position in the production tube. Having released plunger 5, the timer cam 64 at a later pre-set time drops spring arm 69 to close circuit 70 and energize relay 71 to stop timer motor 62 (circuit 61 is opened), and to open the lift gas valve 20 (circuit 60 is closed); also relay 71 is simultaneously de-energized by the opening of switch 72. It may be noted now that cam 26 is operatively ready to function again upon return of the plunger from the well. Thus, the timing sequences of the pumping system have been completed and will be automatically and cyclically repeated upon each return of the plunger with a load of oil from the bottom of the well. As an added safety feature, it will be noted that in case of electric power failure solenoid 59 becomes de-energized, thus allowing valve 20 to shut off the lift gas supply from line 19.

The improved gas-lift control system of this invention was experimentally field tested in a California oil-gas well of 6,063 feet depth, having a lift depth of 5,760 feet below which there extended a tail pipe of 186 feet dipping below the surface of accumulating well liquids. The total time of a pumping cycle was 20 minutes, operationally divided as follows: 6 minutes to raise column of oil at a gas pressure of 200 p. s. i., 8 minutes plunger rest on catcher 21, and 6 minutes time elapse after release and dropping plunger before turning on the gas supply. An average monthly production of 2,232 bar-

rels of oil and 349 barrels of water was obtained at a gas/total liquids ratio of 1.320 cubic feet gas/barrel. These results may be compared with a conventional gas-lift system wherein an intermitter control system based on substantially free flowing gas, wherein the cycling was controlled to some extent by gas pressure buildup to a pre-set lift pressure while the plunger remained at rest at well bottom during influx of well liquids to the production tubing. In the conventional pumping operation, which preceded the installation of my improved pumping system, there was produced an average monthly rate of 961 barrels of oil and 245 barrels of water at gas/total liquids ratio of 2.727 cubic feet gas/barrel. Both of the foregoing pumping operations were conducted to produce at maximum capacity, from which it will be readily seen that my improved pumping system not only required less than half the gas energy, but also more than doubled the productive capacity of the well by a more efficient utilization of pumping time. Moreover, these results show that a remarkably unexpected reduction in water yield was obtained by my improved pumping system.

It is apparent that many modifications and variations of the invention as hereinbefore set forth may be made without departing from the spirit and scope thereof. The specific embodiments described are given by way of example only and the invention is limited only by the terms of the appended claims.

I claim:

1. An improved gas-lift pumping system for use in a well consisting of: a gas injection tube, a well head, a production tube extending downward from the well head, a plunger within the production tube adapted to travel freely substantially the full length of said production tube and into said well head, a footpiece assembly connecting the injection tube in direct fluid communication with the production tube at the bottom thereof, a check valve within the production tube adjacent the foot-piece to prevent loss of fluid to the well formation, a plunger catcher in the well head, a lift gas pressure control valve in said gas injection tube, means for closing said lift gas pressure control valve by the upward movement of said plunger consisting of a trip mechanism actuated by the plunger and operatively connected to said lift gas pressure control valve, a manually adjustable dual timing device connected to said plunger catcher and said trip mechanism and actuated by said trip mechanism for releasing the plunger catcher upon the lapse of the first time period set on said timing device and said timing device also being operatively connected to the lift gas pressure control valve for opening said control valve upon the lapse of the second time period set on said timing device.

2. An improved gas-lift pumping system for use in a well consisting of: a gas injection tube, a well head, a production tube extending downward from the well head, a plunger within the production tube adapted to travel

freely substantially the full length of said production tube and into said well head, a foot-piece assembly connecting the injection tube in direct fluid communication with the production tube at the bottom thereof, a check valve adjacent the foot-piece to prevent back flow of well fluids into the injection tube, a check valve within the production tube adjacent the foot-piece to prevent loss of fluid to the well formation, a plunger catcher in the well head, a lift gas pressure control valve in said gas injection tube, means for closing said lift gas pressure control valve by the upward movement of said plunger consisting of a trip mechanism actuated by the plunger and operatively connected to said lift gas pressure control valve, a manually adjustable dual timing device connected to said plunger catcher and said trip mechanism and actuated by said trip mechanism for releasing the plunger catcher upon the lapse of the first time period set on said timing device and said timing device also being operatively connected to the lift gas pressure control valve for opening said control valve upon the lapse of the second time period set on said timing device.

3. An improved gas-lift pumping system for use in a well consisting of: a gas injection tube, a well head, a production tube extending downward from the well head, a plunger within the production tube adapted to travel freely substantially the full length of said production tube and into said well head, a foot-piece assembly connecting the injection tube in direct fluid communication with the production tube at the bottom thereof, a check valve adjacent the foot-piece to prevent back flow of well fluids into the injection tube, a plunger catcher in the well head, a top bumper spring assembly within the production tube beyond the plunger catcher, a check valve within the production tube adjacent the foot-piece to prevent loss of fluid to the well formation, a lift gas pressure control valve in said gas injection tube, means for closing said lift gas pressure control valve by the upward movement of said plunger consisting of a trip mechanism actuated by the plunger and operatively connected to said lift gas pressure control valve, a manually adjustable dual timing device connected to said plunger catcher and said trip mechanism and actuated by said trip mechanism for releasing the plunger catcher upon the lapse of the first time period set on said timing device and said timing device also being operatively connected to the lift gas pressure control valve for opening said control valve upon the lapse of the second time period set on said timing device.
